TAPE APPLICATOR

Guy J. Delbert, Wheeling, W. Va.

Application May 17, 1954, Serial No. 430,306

1 Claim. (Cl. 216—33)

The present invention relates to tape dispensers and is more particularly concerned with a combination adhesive tape dispenser, applicator and severer.

The principal object of the invention is to provide a device for supporting a roll of tape having an adhesive upon only one surface thereof and accompanying structure whereby the tape can be applied to a surface for sealing purposes, severed when sufficient lengths of the tape are so applied and the end portion of the tape retained ready for further use when required.

Another and equally important object of the invention is to provide a device which can be economically produced rendering the same commercially feasible as a tape applicator and which applicator requires only one hand of the user to apply various lengths of tape to surfaces and sever the tape as required.

A still further important object of the invention is to provide a holder for a roll of tape preferably of the type having a pressure sensitive adhesive upon the surface thereof which holder can be fabricated from sheet material and yet is sufficiently sturdy to press the tape in position when being applied as well as the twists occurring during the severing of the tape.

Another object of the invention is to provide a tape applicator that eliminates the use of rollers and has a tape end guide and storing member which permits ready access to the roll of tape for placing the tape end in position for being retained with its adhesive surface covered until required for further use.

Further objects of the invention will be in part obvious and in part pointed out in the following detailed description of the accompanying drawings, wherein:

Fig. 1 is a side elevation of one form of the present device.

Fig. 2 is a front end view taken in the direction of the arrow A of Fig. 1.

Fig. 3 is a top plan view of Fig. 1.

Fig. 4 is a further side elevation of the present device taken from the side opposite to Fig. 1.

Fig. 5 is a longitudinal section taken on line 5—5 of Fig. 3.

Fig. 6 is a vertical section taken on line 6—6 of Fig. 1.

Fig. 7 is a vertical section taken on line 7—7 of Fig. 5.

Fig. 8 is a horizontal section taken on line 8—8 of Fig. 1.

Fig. 9 is a side view similar to Fig. 1, but partially in section showing the device as used for applying an adhesive tape to a surface.

Fig. 10 is a longitudinal section of a device similar to Fig. 5, but showing the device for dispensing and severing a length of tape.

Fig. 11 is a top view of a tape guide and retainer forming part of the present invention.

Fig. 12 is a longitudinal section taken on line 12—12 of Fig. 11.

Fig. 13 is a lateral section taken on line 13—13 of Fig. 11; and

2

Fig. 14 is a longitudinal section of a modified form of the invention.

Referring more in detail to the accompanying drawings wherein like and corresponding parts are designated by similar reference characters, numeral 1 refers to a side plate of the body of the present tape applicer which has a similar side plate 1a. Side 1 has a ring shaped portion 2 from which extends a circular inwardly tapering flange 4. Side 1a has a similar ring shaped portion 3 with an annular inwardly tapering flange 5. Said flanges are diametrically opposite to one another and are insertable within the roll of tape A for rotatably supporting the same.

Side 1 further has a forwardly extending leg 6, while side 1a has a similar leg 7. Said legs 6 and 7 are connected together by an intermediate section forming a finger support 8, finger retainer 9, front end 10 which extends vertical, and from which bottom 11 extends on a slant to a presser foot 12. This intermediate section extends contiguously and substantially at right angles to and between the sides 1 and 1a. Presser foot 12 is rounded in a longitudinal direction and extends below the bottoms 13 and 14 of said side plates.

Side plates 1a has a semi-circular recess extending upwardly from its bottom 14 for a purpose to be further explained.

Leg 6 further has an L-shaped flange 16 at the free end thereof, while side 1a has a similar but oppositely directed flange 17. A tape severing plate 18 is insertable between said flanges 16 and 17 and end 10 with its toothed cutting edge 19 extends below the bottom of said end.

A tape guide and retainer is specifically shown in Figs. 11, 12 and 13 and this retainer consists of a bar 20 from the opposite ends of which extend a pair of spaced apart parallel hooks 21 and 22 which are substantially U-shaped and have their ends 23 and 24 respectively for insertion each into one of the openings 25 and 26 formed in side plate 1. A pair of fingers 27 and 28 extend substantially perpendicular from bar 20 terminating in an S-shaped hook end portion 29 and 30 respectively for being snapped over the bottom edge 14 of side 1a for retaining said fingers laterally across said bottoms 13 and 14 of sides 1 and 1a. Finger 28 is positioned adjacent the side of presser foot 12 forming a tape opening 31 therewith.

In Fig. 14, there is shown a modified form of tape applicator similar to the device previously described except that in lieu of the tape guide and applicator 20—30 inclusive, a plate 32 extends contiguously between the bottoms 13 and 14 of said side plates 1 and 1a respectively and has a coiled side 33 which with the presser foot 12 forms a tape guide opening 31.

In the operation of the present device, a roll of tape preferably of the type having a tacky and non-drying adhesive upon one face thereof which adhesive will stick to a surface upon the application of pressure to the non-adhesive side of the tape is mounted upon the flanges 4 and 5 by separating plates 1 and 1a which due to the resiliency of the material will snap back with said flanges entering the bore of said roll A. The tape will normally

retain its rolled condition due to the adhesive surface thereof somewhat sticking to the non-adhesive surface therebeneath. The free end portion B of the roll A is inserted through guide opening 31 whereupon it will assume the position as shown in Fig. 5 of the drawing.

That is, below, but spaced from presser foot 12 with the adhesive surface facing downwardly. To assist in quickly and easily withdrawing said free end B from the roll, hooks 29 and 30 are unsnapped from side 1a permitting fingers 27 and 28 to drop downwardly by hooks 23 and 24 sliding through openings 25 and 26 of side 1. This unsnapping can be quickly effected by inserting a finger in recess 15 and forcing downwardly upon one of said fin-

gers 27 or 28. The end portion B can then be pulled from the roll. Upon returning fingers 27 and 28 to their horizontal position and resnapping hooks 29 and 30 over the bottom edge of side 1a, finger 28 will engage the end portion B and push the same forwardly under the presser foot 12 due to said finger 28 being very close to the side of said presser foot and also forwardly of the periphery of the roll A. When it is desired to apply the tape to a surface, the present device is held in one hand as shown in Fig. 9 of the drawing with the forefinger pressing on the finger plate and stop 8 and 9. This finger plate is positioned above the bottom 11 and therefore to one side of the presser foot 12 causing the device to pivot upon said presser foot with the forward end moving downwardly as permitted by the slanted bottom 11, raising the portions 2 and 3 upwardly into the palm of the user's hand. The presser foot 12 then presses upon the tape B therebeneath pulling the applier along in the direction to which the tape is to be applied, the tape will unreel from the roll A and adhere to the surface therebeneath.

As soon as a sufficient length of tape has thus been applied, further downward pressure on the forefinger and a twisting motion of the entire device will place the cutting teeth 19 across the tape for quickly and easily severing the same. As shown in Fig. 10, a length of tape can be pulled from the roll A and severed therefrom by pressing one finger against the tape beneath the presser foot and then pulling the tape across the teeth 19.

After the tape has been so severed, the free end thereof can be drawn backwardly across the fingers 27 and 28 as shown in Figs. 1 and 4 of the drawings. The adhesive will temporarily retain the tape across said fingers with the non-adhesive side positioned below the applier. By simply inserting the finger in recess 15, the tape can be pulled loose from said fingers 27 and 28 whereupon it will again assume its position beneath said presser foot and be ready for further use.

It is to be appreciated that the pressures applied to the present applicator when in use are in the vicinity of the legs 6 and 7 which are firmly held together by the intermediate section forming the portions 8 and 12 inclusive. The portions 2 and 3 are free for being separated for readily receiving the roll A. The end 10 can be an intermediate section of a piece of sheet material with the sides 1 and 1a extending therefrom and the finger support 8 as well as the bottoms 11 and 12 can be formed from the top and bottom of said intermediate section and fastened to legs 6 and 7 in any suitable manner such as by curled end portions extending over said legs. Fur-

ther, fingers 27 and 28 tend to prevent the spreading of the lower part of said plates 1 and 1a when in use. The edges of the sheet material are indicated as being rolled in the drawings for the purpose of adding stiffness thereto. A plastic or metallic material may be used.

The present device is capable of considerable modification and such changes thereto as come within the scope of the appended claim are deemed to be a part of the invention.

10 I claim:

A tape dispenser and applier comprising a casing having a substantially U-shaped longitudinal configuration with the base of said casing forming an end wall and the legs a pair of substantially parallel resilient side walls free at their outer ends, projections carried by said walls for rotatably and detachably supporting a roll of tape therebetween, a bottom plate connected to and extending from said end wall along and connecting the lower edges of a portion of said side walls adjacent said end wall, said bottom plate having a longitudinally curved semi-circular portion positioned outwardly of said side wall lower edges forming a tape presser foot, a finger pivotally connected to the medial portion of one of said walls adjacent the lower edge thereof and capable of extending to the medial portion of the other of said walls for guiding the tape from a roll to and beneath said presser foot, means for connecting said finger to the other of said walls for detachably connecting said walls holding said tape roll therebetween, said end wall having a further extension extending between said side walls adjacent the upper edges thereof and above said presser foot providing a finger rest for permitting the manual pressing downwardly of said casing and a cutter blade carried by said end wall with the cutting edge thereof being below said side wall 20 lower edges.
